UNITED STATES PATENT OFFICE.

JERVIS R. HARBECK, OF DETROIT, MICHIGAN, ASSIGNOR, BY MESNE ASSIGNMENTS, TO DETROIT CAN COMPANY, OF DETROIT, MICHIGAN, A CORPORATION OF NEW JERSEY.

PROCESS FOR FORMING TUBES.

1,072,715.

Specification of Letters Patent.

Patented Sept. 9, 1913.

Application filed March 5, 1908. Serial No. 419,277.

To all whom it may concern:

Be it known that I, JERVIS R. HARBECK, a citizen of the United States, and a resident of Detroit, in the county of Wayne and State of Michigan, have invented a new and useful Process for Forming Tubes, of which the following is a specification.

My invention relates to the manufacture of tubes from fibrous material, and its object is the economical production of tubes of non-circular cross-section such as square, triangular or any other design not easily produced directly by winding.

My invention consists in a process comprising the winding of approximately cylindrical tubes, and while such tubes are in plastic, non-resilient condition, forming them to the desired cross section, and then permitting them to harden.

While this process may be carried out in connection with presses and molds, it is rapidly and easily carried out by means of such machines as are illustrated in the accompanying drawing, in which—

Figure 1 is a side view of a plurality of sets of rolls adapted for forming tubes rectangular in cross section. Fig. 2 is an end view of the last set of these rolls. Fig. 3 is an end view of a set of rolls adapted for forming tubes triangular in cross section.

Similar reference characters refer to like parts throughout the several views.

While I have been able to convolutely wind container bodies of various cross sections on the proper mandrels, I have found that a larger number of bodies can be produced by first winding the tube material into tubes on a continuous tube machine and then cutting the long lengths into container bodies. But forming non-cylindrical tubes continuously has hitherto not been accomplished.

My present invention has for its object the changing of the cross section of cylindrical tubes to that of any of the desired forms.

In the drawings, 1 is a base to which are secured a number of frames 2, in which are journaled the rollers 3, geared together by means of the pinions 4. These rollers may be driven by means of the sprocket chain 5 and sprocket wheels 6 from any source of power.

A tube 7, still moist and soft from the winding machine is introduced and passed

through between the different sets of rolls, being first but slightly flattened, each succeeding set continuing the action, until the tube as it comes from the last set of rolls has the desired cross section. The number 60 of sets of rolls will depend upon the thickness of the tubing and upon the material. After the tubes have been formed, they are stored until the cement becomes dry and the tubes resilient. They may then be cut into 65 proper lengths and if to be used for container bodies, heads are attached.

The cylindrical tubes must be operated upon through this process while they are still plastic and non-resilient, that is, before the cement employed to hold the several layers together has had time to harden.

Where triangular tubes are desired, a plurality of sets of rolls such as shown in Fig. 3 may be employed, comprising a frame 11, 75 rolls 12 geared together by pinions 13 and driven by the sprocket wheel 14. Any other combination of rolls or devices may be employed to produce any desired cross section.

All that is necessary to carry out this process are tubes that are plastic and non-resilient, and means to give the tubes the desired form. The tubes must be permitted to become hard before being handled sufficiently to change the new form. 80

Having now described my process, what I claim as my invention and desire to secure by Letters Patent is:—

1. The process of making tubes of fibrous material of any desired cross section, which 90 consists in winding moist, plastic, non-resilient tubes of such cross section as may be easily produced, then subjecting the hollow tubes to external pressure on all sides of the center and changing the cross section by 95 means of successive sets of rolls to that desired while the tubes are still plastic and non-resilient, and then permitting the tubes to dry out and harden.

2. The process of forming tubes, which 100 consists in winding soft, cement-coated fibrous material into approximately cylindrical tubes, then subjecting the hollow tubes to external pressure on all sides of the center and changing the cross section of the tubes before the material becomes dry and non-plastic, and then permitting the tube to harden. 105

3. The process of making tubes of fibrous material of any desired cross section, which 110

consists of re-forming cement-coated plastic, non-resilient tubes subjecting the hollow tubes to external pressure on all sides of the center to change the cross section of the

5 tubes and then permitting them to harden.

4. The process of making tubes of fibrous material of any desired cross section which consists of winding cement-coated fibrous material into plastic, non-resilient tubes subjecting the hollow tubes to external pressure

10 on all sides of the center to change the

cross section of the tubes, then changing the cross section of such tubes while still non-resilient and then permitting them to harden.

In testimony whereof, I have signed this specification in the presence of two subscribing witnesses.
